HANDLE FOR FOLDABLE-FLAT UMBRELLA

Paul Kraft, Geislingen, Steige, Germany, assignor to Bremshey & Co., Ahrstr, Germany

Filed Apr. 10, 1968, Ser. No. 11,386

Claims priority, application Canada Jan. 26, 1968

Term of patent 7 years

Int. Cl. D3—03

U.S. Cl. D88—3

FIG. 4

FIG. 1

FIG. 2

FIG. 3

The umbrella shaft is shown by fragmentary phantom lines for purposes of illustration only.

I claim:

The ornamental design for a handle for foldable-flat umbrella, as shown and described.
